UNITED STATES PATENT OFFICE.

ZEBULON DAVIS, OF CLEVELAND, OHIO, ASSIGNOR TO THE STANDARD LIGHTING COMPANY, OF SAME PLACE.

VAPOR-BURNER STOVE.

SPECIFICATION forming part of Letters Patent No. 325,592, dated September 1, 1885.

Application filed December 13, 1884. (No model.)

To all whom it may concern:

Be it known that I, ZEBULON DAVIS, of Cleveland, in the county of Cuyahoga and State of Ohio, have invented certain new and 5 useful Improvements in Vapor-Burner Stoves; and I do hereby declare the following to be a full, clear, and exact description of the invention, such as will enable others skilled in the art to which it pertains to make and use it, 10 reference being had to the accompanying drawings, which form part of this specification.

My invention relates to an improvement in vapor-burners; and it consists, first, in the combination of the generating-burner, a support therefor, a pipe for conducting the vapor, the conducting-pipes, having their inner ends turned at an angle to their length, and needle-valves located outside of and beyond the ends 15 of the pipes; second, the combination of the generating-burner, a support therefor, a pipe for conducting the vapor, the conducting-pipes, having their inner ends turned at an angle to their length, needle-valves for controlling the flow of vapor, and a suitable 20 means at the inner ends of the pipes for the purpose of preventing the flame from one burner from interfering with the flame of the other burner; third, a vapor-burner provided 25 with two horizontal rows of apertures and having a tube formed therewith and in between the two rows of apertures, the tube being formed partly within and partly without the burner, all of which will be more fully 30 described hereinafter.

Figure 1 is a side elevation of a burner embodying my invention. Fig. 2 is a vertical section of the burner alone. Fig. 3 is a detail view of the conducting-pipes and their burners. Fig. 4 is a detail view of a slight modification made in the inner ends of the conducting-pipes. Fig. 5 is a detail view of one of the burners which is used upon the outer end of one of the conducting-pipes. Fig. 6 is an 40 inverted view of a portion of the burner. Fig. 7 is a perspective of the burners and their attachments.

A represents a stand-pipe, and B the generating pipe or tube which extends therefrom, 45 and which is cast in a single piece with the burner b, as shown in Fig. 2. This tube or

chamber extends horizontally around the burner, and is located midway between the two rows of apertures in the burner, so that the flames from both rows of apertures will 55 play upon this tube or chamber and heat it to a very intense degree, even when the flames are turned down low. This tube, being located as here shown, and being heated to such an intense degree, generates vapor rapidly and 60 in sufficient quantities not only to supply this central generating-burner, but the burners which are placed upon the conducting-pipes at a suitable distance beyond it.

Heretofore a generating tube or chamber 65 has been formed around the extreme upper portion of a wire gauze burner; but in this case the tube or burner is placed in such a position that it is only affected by the heat of a single row of apertures. By locating this 70 tube in between two rows of apertures, as here shown, it is heated both above and below, and a greater amount of vapor is generated. When this central burner is not in use, in order not to waste fuel, the flame 75 should be turned down as low as possible, and then this central burner serves as a generator for the burners placed upon the conducting-pipes. As the gas must be generated rapidly 80 to supply both burners, it is necessary that this 85 tube or chamber should be thoroughly heated, even when the flame of the central burner is turned down. Where the tube or chamber is located at the top of the burner and only affected directly by a single row of apertures, 90 a sufficient quantity of gas cannot be generated to supply other burners when the flame is turned down.

The vapor-tube B' has a needle-valve, D, passed through it at right angles, as shown 95 in Fig. 1, for the purpose of supplying vapor to this central burner. The lower end of the vapor-tube, as shown in Fig. 6, has its end turned in opposite directions, and the escape of the vapor from each end regulated by a 95 needle-valve, F. These needle-valves F preferably extend horizontally outward, and are placed entirely outside of and beyond the two ends of the conducting-pipes G, in contradistinction to being located between the pipes. 100 These two valves F are provided, respectively, with right and left threads, and the outer end of

each screw is provided with a handle, H, as shown in Fig. 3. The needle-valves, having threads which are cut in opposite directions, are moved in opposite directions for the purpose of turning on and shutting off the vapor. These valves, being located beyond the ends of the conducting-pipes, as here shown, enable needle-valves to be used, which cannot be done where the valves are located between the ends of the pipes, as has heretofore been done. Where needle-valves are used the points of the needles always keep the apertures open; but where plug-valves are used, as must be done where the valves are located between the ends of the pipes, the vapor-apertures soon become clogged from the heavy carbonaceous matter in the oil or fluid, and then the stove is rendered utterly inoperative until this matter has been cleaned out. As this cannot be readily done by inexperienced persons, and especially when the stove is hot, the stove becomes practically disabled, and thus much trouble and annoyance is caused.

The conducting-pipes G have their inner ends turned at an angle to the length of the pipe, and secured together, as shown, just beyond the points of the needle-valves, as shown in Fig. 6. In the outer sides of these ends are formed suitable openings, I, so that when the flame follows the gas back through one of the pipes when the burner is shut off, and thereby causes a slight explosion of the gas, the flame will be projected outward from the opening I, and away from the other burner, and thus prevent the fire of one communicating with the vapor of the other. Where the openings I are not used for this purpose, a partition, J, may be extended from the ends of the pipes in between the two burners, as shown in Fig. 4, and thus effect the same object. Where no means are taken to prevent the flame from one burner communicating with that of the other, when one burner is shut off a slight explosion follows, which will sometimes not only put out the flame of the burner upon the other conducting-pipe, but also put out the flame of the generating-burner at the same time. If this extinguishment of the other burners is noticed, they can be readily lighted again, but if it is not noticed the escape of the vapor and fluid takes place through them, to the great danger not only of the operator, but to the building in which the stove is being used.

Upon each conducting tube or pipe G are placed one or more burners, O, which are preferably made of light perforated sheet metal, as shown in Fig. 5. If the flames burn

directly from the apertures through this sheet metal, the heat soon destroys it. In order to prevent this I take a cylinder, a, formed of a coiled wire, or a jacket made of thicker and heavier metal, and place it around the thin perforated metal, so that the flame will burn from the wire or perforated jacket rather than from the thin perforated metal. The jacket or cylinder serves to keep the flame from direct contact with the perforated metal, while the thin perforated metal serves to keep the flame from passing back into the conducting-pipe. By means of a protector formed in this manner the thin perforated metal can be made to last much longer than where no jacket or protection is used. Inside of the burner, upon its bottom, is placed a thin perforated piece of metal or wire-gauze, P, which serves to prevent the flame from following back through the pipe when the vapor is shut off. The burner becomes so intensely heated that the vapor catches fire from the inner side of the burner, and then the flame follows back through the pipe to the needle-valves, as already described. This guard, which is placed inside of the burner, serves to prevent the flame from passing back into the pipe.

Having thus described my invention, I claim—

1. A vapor-burner, b, provided with two horizontal rows of apertures, and having a tube, B, formed therewith, and in between the two rows of apertures, the tube being formed partly within and partly without the burner, substantially as shown.

2. The combination of a generating-burner, a suitable support therefor, a pipe, B', for conducting the vapor, with the conducting-pipes, having their inner ends turned at an angle to the length of the pipe, and the needle-valves located at the ends of the pipes, substantially as set forth.

3. The combination of a generating-burner, a suitable support therefor, a pipe, B', for conducting the vapor, with the conducting-pipes, having their inner ends turned at an angle, the needle-valves located outside of and beyond the ends of the pipes, and a suitable means at the inner ends of the pipes for the purpose of preventing the flame from one burner from interfering with the other burners, substantially as specified.

In testimony whereof I affix my signature in presence of two witnesses.

ZEBULON DAVIS.
